WILLIAM M. WHEILDON, OF ASHLAND, AND EDWARD H. ANGIER, OF FRAMINGHAM, MASSACHUSETTS; SAID WHEILDON ASSIGNOR TO SAID ANGIER.

PACKAGING TORIC ARTICLES.

1,366,547.

Specification of Letters Patent. Patented Jan. 25, 1921.

Application filed March 22, 1917. Serial No. 156,722.

To all whom it may concern:
Be it known that we, WILLIAM M. WHEILDON and EDWARD H. ANGIER, citizens of the United States, and residents of Ashland and Framingham, respectively, in the county of Middlesex and Commonwealth of Massachusetts, have invented an Improvement in Packaging Toric Articles, of which the following description, in connection with the accompanying drawings, is a specification, like characters on the drawings representing like parts.

This invention relates to the art of packaging toric articles. By this we refer to articles which may be considered as solids generated by the revolution of a plane figure about an axis in its own plane and thus having a longer outer dimension and a shorter inner dimension. As an example of such articles we may mention the shoe of a pneumatic vehicle tire in which case the revolution is a complete one and the article is annular in form. The purpose of our invention is to provide an improved method of wrapping such articles with an inclosing covering of paper or similar material and one form of mechanism by means of which the method may be expeditiously practised. For convenience in description we shall refer to the article operated on as a tire, using this word in an exemplary sense as typifying various articles of toric form.

Our invention may best be understood by reference to the following description taken in connection with the accompanying drawings, wherein—

Figure 1 is a side elevation of an illustrative form of machine constructed in accordance with our invention;

Fig. 2 is a central, longitudinal section through the same, with parts broken away;

Fig. 3 is a section on the line 3—3 of Fig. 1, the number 17 being in dotted line position;

Fig. 4 is a plan view showing the power transmission mechanism; and

Fig. 5 is a section through a tire wrapped by the machine shown in Figs. 1 to 4.

The method of wrapping tires which forms a part of our invention is exemplified by the operation of the machine disclosed and may readily be understood by a description of the action of that machine, the various mechanical parts being described in connection with the operations which

they perform. For the sake of brevity we shall, therefore, first describe the construction of the machine and the manner of its operation. The operation of wrapping the tire is commenced with parts of the mechanism in the dotted-line position shown in Fig. 1. The mechanism there shown is carried by a framework embodying an annular frame 7 and two standards 9. The standards 9 form bearings for shafts 11 and 13 respectively which carry at their proximate ends the circular disks 15 and 17. The shafts 11 and 13 are threaded with right and left-hand threads respectively at their distal ends, which threaded portions coöperate with nut-like portions 19 on frame pieces 21 connected and held against rotation by rods 23 extending between them and guided in the annular frame 7.

Mounted adjacent one of the standards 9 is an arm 24 free to rotate with respect to the shaft 13 but normally held against rotation by a catch 25 engaging a portion of the standard. The arm 24 has an angular extension 27 provided with a segmental seat 29 upon which a tire may be placed in the position shown in dotted lines in Fig. 1.

The two disks 15 and 17, among other functions, are supports for the tire during the wrapping operation. Their particular structure can best be understood by reference to Fig. 2 wherein it is seen that the disks are provided with fingers 31 having beveled ends and adapted to fit together in staggered relation, the recesses between the fingers being so formed that when the two disks are together with the fingers mating, a smooth surface will be presented to support the tire. Each of the disks has a flange 33 adapted to engage the tire beads in such manner that the coöperating disks will form a structure somewhat similar to the tire-holding rim of a wheel as will be readily understood by inspection of Fig. 3. The disks also have outwardly extending and laterally flaring wing portions 35 having at their outer edges seats 37 for a purpose presently to be described.

Means are provided for moving the two members 15 and 17 toward and from each other to provide either an open space between them by means of which a tire may be introduced thereto, or to clamp them together. In the present embodiment of the

invention the disks are power driven. For this purpose each of the standards 9 is bifurcated in the manner illustrated in Figs. 1 and 2 to provide a bearing for sprocket 5 wheels 39 having feathers engaged with grooves 41 on the respective shafts in such manner as to permit the shafts to slide relatively to the wheels, but to cause the wheels to rotate the shafts. Power is applied to the 10 shafts from any suitable source herein typified by an electric motor 43. The transmission mechanism is best shown in Figs. 2, 3 and 4, and we shall herein refer more particularly to Figs. 3 and 4 in describing the 15 same. The sprockets 39 are connected by suitable chains with driving sprockets on a shaft 45. Surrounding this shaft but normally free to turn with respect thereto, are two clutch drums 47 and 49 continuously 20 driven from the rotor of the motor. In the present embodiment of the invention the drum 47 is driven by a geared connection and the drum 49 is driven in the opposite direction by a chain. Each of the drums is 25 formed with a concave frusto-conical surface adapted to coöperate with one of the similar convex surfaces 51 on a sliding clutch member 53 splined on the shaft 45 as best shown in Fig. 3. The sleeve may be 30 moved to the right or left as desired by means of the lever 55 carried by a rock shaft 57 and controlled by the pedal member 59. If one side of the pedal is depressed the shaft will be clutched to the drum 47 35 and driven in one direction, whereas if the other side is depressed the shaft will be clutched with the drum 49 and its motion reversed. When the shafts 11 and 13 are rotated, the parts 19 will act as nuts and the 40 two disks 15 and 17 will be fed toward or from each other, as the case may be.

Having thus described certain parts of the mechanism of the machine shown, it will probably promote a ready understanding thereof to describe the function of these parts. Referring, therefore, particularly to Fig. 1, supposing the parts to be in the position shown in dotted lines, the tire *a*, assembled with an interior, circumferential 45 strip *b* preferably gummed on its inner face, is placed in position on the seat 29 between the two disks 15 and 17. The pedal 59 is then depressed to clutch shaft 45 to the motor and cause the two disks 14 and 15 50 to approach each other. It will be noted by reference to this figure that the disk is somewhat eccentric to the tire mounted on the seat 29. The beveled fingers 31, however, will enter the interior of the tire, lift the 55 same from the seat 29 and center it. The motion of the disks 15 and 17 continues until the fingers 31 have nested and the flanges 33 have engaged the beads of the tire in the manner shown in Fig. 3.

60 The next step is to apply a strip of

wrapping material circumferentially about the tire. For this purpose the arm 24 may be made to guide the strip, and herein we have shown a small roll of paper 61 carried by an angular extension 62 of said arm opposite the extension 27. The end of the paper is drawn from the roll 61 and held in position against the seats 37. The arm 24 may then be unlatched by rocking the catch 25 and the roll rotated about the tire 70 supported by the disks 15 and 17 to wrap a strip in position on seats 37 and in complete encircling relation to the tire. When this is done the paper may be cut by means of the knife 63 and the ends, if desired, temporarily secured. At this stage of the operation the tire *a* has been assembled with the materials for wrapping it including an inner strip *b* and the encircling wrapper strip *c*, and all these parts are in position on a 80 suitable holder in readiness for the operation of suitable mechanism thereon to shape the wrapping material about the tire and to complete the package.

The next step in the operation of the machine is to bring the strip-encircled tire into operative relation to the devices which wrap the edges of the strip about the sides of the tire, which devices herein are carried by the annular frame 7. To permit 90 this to be done, the support formed by the two disks 15 and 17, together with their shafts and the connecting frames 21, may be shifted as a whole in the bearing standards 9. For this purpose a lever 65 is provided 95 which when rocked will shift the parts from the dotted-line position in Fig. 1 to the full-line position, the rods 23 sliding in their bearings in the annular frame 7. This will bring the parts to the position illustrated in 100 Fig. 2 with the tire centered within the annular frame 7 and having a sheet of paper *c* encircling the same as there illustrated. In the present embodiment of the invention the strip *b* is folded about the tire by wiping 105 devices which shape the paper to the cross-section of the tire at a plurality of points spaced about the tire circumference and the fullness of the paper between these points is thereafter smoothed out into the form 110 of plaits. Herein a plurality of wiping devices are carried by the annular frame 7 and arranged to operate simultaneously in substantially radial planes. In the illustrative machine the devices are moved in and 115 out in planes which are exactly radial, but it will be understood that the motion is not so strictly limited.

The wiping devices may embody spring 120 yokes 67 of a form corresponding substantially to the cross-sectional contour of the tire and mounted on rods 69 extending radially through the frame 7. The rods 69 are provided with teeth 71 forming racks and adapted to mesh with a spiral thread 73 (see 130

Fig. 3) on a ring 75 in-set in the side of the frame 7. When the ring 75 is rotated the spiral, acting on the racks, will move the wipers in or out according to the direction 5 of rotation of the ring. The mechanism is similar to the well-known scroll chuck.

The ring 75 may have exterior spur teeth and be driven from a pinion 77 mounted on a shaft 79. In Fig. 4 the transmission 10 mechanism for driving the pinion shaft is most clearly shown. Drums 81 and 83 are mounted loosely on the shaft and driven in opposite directions by belts connected to the drums 47 and 49 which, it will be remembered, are constantly driven in opposite directions from the rotor of motor 43. The drums 81 and 83 have conical cavities adapted to coöperate with the conical clutch surfaces on sleeve 85 which slides on shaft 20 79. The sleeve 85 may be shifted along the shaft by yoke 87 on rock shaft 89 which is controlled by pedal 91. The mechanism is similar to that controlling the shaft 45. By clutching the shaft to one or the other of 25 the drums 81 and 83, the pinion may be rotated in either direction desired to move the wipers 67 inwardly or outwardly.

Referring again to Fig. 2 it is clear as 30 the wipers 67 approach the center they will fold the paper strip *c* about the tire *a* shaping it thereto at various points to its circumference. Because of the shorter circumference of the tire at the bead, as compared with the tread, there will be a certain fullness 35 of wrapping material between the several points. When the wipers have been brought to their innermost position, their movement is halted and the pedal 59 is next manipulated to draw the disks 15 and 17 apart. The tire will remain suspended in 40 the same position, being sustained by the members 67 clamped thereabout. The withdrawal of the disks will permit edges of the paper strip to project inwardly beyond the 45 beads of the tire. Opportunity is taken at this time to moisten the adhesive face of the strip *b* and the pedal 59 is then manipulated to close the disks 15 and 17 once again. In this movement the fingers 31 will engage the 50 projecting edges of the strip *c* and fold them inwardly over the beads of the tire and into contact with the sticky face of the strip *b* thus completing the wrapping about the tire and forming a sealed package. It will be 55 noted that the disks 15 and 17 as they approach each other have a rotary motion in the same sense. Consequently, the flanges 33 will wipe along the sides of the tire with a circumferential rubbing motion and will 60 smooth out or flatten the fullness of the paper between the several wipers 67 forming it into plaits and causing the paper to fit the tire in a neat manner.

After the wrapping operation has been 65 completed as described, the wipers 67 may

be withdrawn, the support comprising the disks 15 and 17 shifted away from the annular frame, the disks drawn apart, and the tire removed.

It may be noted that the power of the 70 motor 43 is applied to the various parts of the mechanism through frictional transmission devices so that there is opportunity for slip at the end of each phase of the machine's motion. Consequently, each step of 75 the process may be thoroughly followed out without any danger of breakage.

In Fig. 5 we have shown a tire which has been wrapped according to the improved method exemplified by this machine. Re- 80 ferring to that figure it will be seen that the tire *a* is inclosed by the strip *c* which is of a width substantially corresponding to the cross-sectional perimeter of the tire, the strip *c* being folded inwardly about the sides 85 of the tire and plaited as shown at *d* to conform thereto. The edges of the strip are folded in at the interior circumference and joined by means of the strip *b* to which they are secured. In Fig. 5 we have also shown 90 another circumferential strip *e* overlying the edges of the wrapping strip *c* to contribute to the security of the package and to provide a neat finish.

It will be noted that the operation of the 95 machine just described exemplifies a method of packaging tires or similar articles which might be carried out by various mechanisms. The one which is illustrated is merely an example of many mechanical structures 100 which might be devised and as regards the machine itself the structural details are obviously capable of considerable modification without departure from the spirit of the invention.

What we claim and desire to secure by 105 Letters Patent is:

1. In a device of the class described, means to support a tire by engagement with the inner circumference thereof and wiping means movable in and out in spaced, substantially radial planes to fold a strip of paper inwardly about the cross-section of the tire and shape the same thereto.

2. In a device of the class described, 115 means to support a tire by engagement with the inner circumference thereof, means temporarily to support a strip of paper in encircling relation thereto, and wiping means movable in and out in spaced, substantially radial planes to fold the strip inwardly about the cross-section of the tire and shape the same thereto.

3. In a device of the class described, 125 means to support a tire by engagement with a circumference thereof, means to draw a strip of paper into encircling relation to the same, and wiping means movable in and out in spaced, substantial radial planes to fold the strip about the cross-section of the tire from 130

the other circumference and shape the same thereto.

4. In a device of the class described, means to support a tire, by engagement with a 5 circumference thereof, means to draw a strip of paper into encircling relation to the same, means temporarily to support the paper in that position, and wiping means movable in and out in spaced, substantially 10 radial planes to fold the strip about the cross-section of the tire from the other circumference and shape the same thereto.

5. In a device of the class described, means to support a tire by engagement with 15 a circumference thereof, and wiping devices comprising spring members substantially conforming to the cross-section of the tire, and means for moving them in and out substantially radially to fold a strip of paper 20 about the tire from the other circumference and shape the same thereto.

6. In a device of the class described, means for suspending a tire by engagement with the inner circumference thereof, means 25 to fold a paper strip inwardly about a tire by pressing the same to the transverse curvature thereof at a series of circumferentially spaced points, and means to smooth into folds the resultant fullness of the 30 paper between successive points.

7. A device of the class described comprising a support for the tire adapted to suspend the same by engagement with a circumference thereof, and a centric group of 35 coradially movable wiping members for folding a wrapper thereabout from the other circumference.

8. In a machine for wrapping tires an 40 annular frame having radially movable wipers to fold a strip about the cross section of a tire and a pair of members having annular portions adapted to approach one another across a circumference of the tire and means for moving them in and out 45 to infold the edges of the strip across that circumference.

9. A device of the class described comprising a temporary support for the tire adapted to position it in the horizontal direction, and a supporting device comprising 50 circular clamping plates to engage the tire on either side movable toward and from the plane of said temporary support and being disposed eccentrically to the tire thereon.

55 10. A machine of the class described comprising a centric group of members operable substantially in radial planes to fold a strip of paper about a circumference and the sides of a tire, and members applicable 60 to the sides of the tire to fold the edges of said strip toward one another at the other circumference, said members having a rotary motion whereby to contract the fullness of the paper about the tire.

65 11. A machine of the class described com-

prising means interiorly engaging a tire to support the same with a paper strip encircling the same, and means for shaping the strip thereabout comprising wiping mechanism arranged for operating motion 70 inwardly at spaced points about the circumference of the tire and circumferentially of the sides thereof.

12. A machine of the class described comprising a tire support for holding a tire by 75 engagement with a circumference thereof, a device for encircling the same with a strip of paper, a device for folding the paper strip about the cross-section of the tire, and means for moving relatively said support 80 and said two devices for presenting the tire on the former to either of the latter.

13. A machine of the class described comprising a support for the tire having lateral wing portions temporarily to support a 85 paper strip in encircling relation to the tire, the support being divided to provide portions applicable to the tire from opposite sides, said portions being arranged for relative to-and-fro movement. 90

14. A machine of the class described comprising a support for the tire having lateral wing portions temporarily to support a paper strip in encircling relation to the tire, and centripetally movable fingers to fold the 95 strip inwardly about the tire.

15. A machine of the class described comprising an annular frame, means for supporting a tire concentrically of the same, wiping devices carried by the frame, and a 100 scroll for moving the same.

16. In a device of the class described, the combined supporting and folding device comprising opposed members having beveled fingers adapted to interfit in staggered relation, the spaces between said fingers being formed to coöperate therewith to provide a smooth tire-supporting surface. 105

17. In a device of the class described, the two supporting members each having a portion laterally to engage the tire bead and a part to extend beneath the bead, said latter portions having coöoperating fingers adapted to nest in staggered relation, and means for causing relative movement of approach and 110 recession between said members.

18. A machine of the class described comprising devices operable to fold a paper strip about the sides of a tire, said devices being adapted to sustain the partly wrapped 120 tire, and means for folding the edges of the strip inwardly toward one another transversely to the plane of the tire.

19. A machine of the class described comprising opposed circular members adapted 125 to coöperate to form a support for the tire, devices operable to fold a paper strip about the tire, said devices being adapted to sustain the partly wrapped tire, and means for moving the members to and from one an- 130

other whereby they may be utilized both as a support and as folding members.

20. A machine of the class described comprising opposed circular members adapted to coöperate to form a support for the tire, wiping devices operable at spaced points about the tire to fold a paper strip thereabout, said devices being adapted to sustain the partly wrapped tire, and means to give said members a combined motion of rotation and of reciprocation toward and from one another.

21. A machine of the class described comprising a pair of members movable toward and from each other and adapted to support a tire by engagement with the inner circumference thereof to permit a strip to be folded about the tread and sides of the tire and means for engaging the exterior of the tire for supporting the same independently of said members.

22. A machine of the class described comprising means for supporting the tire by engagement with the inner circumference thereof, means movable inwardly over the

tire sides to fold a strip about the tread thereof and means to withdraw said supporting means and fold the strip in over the interior circumference of the tire.

23. A machine of the class described comprising means for folding both edges of an encircling strip inwardly over the sides and toward the center of the tire and means for thereafter folding the edges axially inwardly toward each other over the inner circumference of the tire. 30 35

24. The method of wrapping tires, comprising the following steps: encircling the tire exteriorly with a strip substantially corresponding in width to the cross-sectional perimeter thereof, simultaneously shaping the strip thereto at spaced points about the circumference, smoothing out the fullness between said points, and joining the strip edges. 40 45

In testimony whereof, we have signed our names to this specification.

WILLIAM M. WHEILDON.
EDWARD H. ANGIER.
